CLAIM

The ornamental design for a protector housing for telecommunication equipment, as shown and described.

DESCRIPTION

FIG. 1 is a front elevational view of a protector housing for telecommunication equipment showing our new design;

FIGS. 2 and 3 are respectively top and bottom plan views thereof;

FIGS. 4 and 5 are respectively left and right side elevational views thereof;

FIG. 6 is a rear elevational view thereof;

FIG. 7 is a front elevational view thereof in opened position;

FIG. 8 is a front elevational view thereof in opened position, and with the compartment door thereto also open; and

FIG. 9 is an exploded bottom plan view thereof in separated, unhinged tandem relationship.

FIG. 1

FIG. 2

FIG. 3

FIG. 4

FIG. 5

FIG. 6

FIG. 7

FIG. 9

FIG. 8
